UNITED STATES PATENT OFFICE.

LOUIS G. PACENT, OF WINFIELD, NEW YORK, ASSIGNOR TO PACENT ELECTRIC COMPANY, INC., OF NEW YORK, N. Y., A CORPORATION OF NEW YORK.

INDUCTANCE-COIL MOUNTING.

Application filed July 24, 1923. Serial No. 577,639.

To all whom it may concern:

Be it known that I, LOUIS G. PACENT, a citizen of the United States, residing at Winfield, Long Island, in the county of Queens, State of New York, have invented certain new and useful Improvements in Inductance-Coil Mountings; and I do hereby declare the following to be a full, clear, and exact description of the invention, such as will enable others skilled in the art to which it appertains to make and use the same.

This invention relates to adjustable inductance coil mountings and more particularly to devices of that character for use in the radio art.

Heretofore, inductance coil mountings have been constructed wherein one coil is held stationary, and one or more other coils are arranged to be moved in a single plane toward or away from the stationary coil.

The principal object of the present invention is to provide a mounting whereby the movable coil or coils may be adjusted in a plurality of planes. Such an arrangement permits of a wider range of coupling between the coils than is possible with the ordinary self-contained inductance mounting.

A further object is to provide simple and convenient operating means for effecting adjustments of the movable coil in a plurality of planes.

The invention consists, briefly, of the combination with an inductance coil of a mounting device for the inductance coil which is adjustable in a plurality of planes.

The principal features of the preferred embodiment of the invention comprise a bearing member arranged to rotate about a vertical spindle, a horizontal shaft journaled in the bearing member, and means carried by the shaft for securing an inductance coil thereto.

A further feature of the invention consists in the provision of an operating handle which serves to effect the adjustments of the movable coil in two planes and in which is also incorporated a set screw whereby the movable coil may be secured in any horizontal position.

Other features will be apparent from the detailed description which follows.

With reference to the accompanying drawings,

Fig. 1 is a plan view of a complete in-

ductance coil mounting with three coils attached;

Fig. 2 is a conventional cross-section taken approximately along the line 2—2 of Fig. 1;

Fig. 3 is a cross-sectional detail view taken along the line 3—3 of Fig. 2; and

Fig. 4 is a cross-sectional view corresponding to Fig. 3, but of an alternative structure.

To the base 4 there is secured an angle iron 5 to which in turn is secured another angle iron or bracket 6. Coils 7, 8 and 9 are preferably of the well-known honeycomb or duo-lateral type and each is secured to a block of insulating material 10 by means of a strap 11 and screws 12. Into each of the blocks 10 there is inserted a pair of metal contact tips 13 to which the terminals of the respective coils are attached.

The block 14 of insulating material associated with the center coil 8 is rigidly secured to the bracket 6, but the blocks 14 corresponding to the outside coils 7 and 9 are mounted by means of the metal plate 15 on a shaft 16.

The metal contact tips 13 are grooved at their ends whereby they are engaged by the spring pressed plungers 17, as shown in Fig. 2, and electrical connection is established between the tips 13 and binding posts 18 through the springs 19. From the binding posts 18, connections may be extended for convenience to binding posts 20 mounted on the base 4. Coils 7 and 9 being carried by shafts 16 are rotatable about the axis thereof as is evident from Fig. 1—knobs 21 of Figs. 1, 2, and 3 being provided for that purpose.

Shaft 16 is journaled in the bearing member 22 which in turn is rotatably mounted on bracket 6 by means of spindle 23. Coils 7 and 9 are therefore rotatable in a horizontal plane toward and away from the fixed coil 3, about the axis of spindle 23. As is shown most clearly in Fig. 3, pin 24 is threaded into bearing member 22 and may be screwed up against spindle 23 to clamp bearing member 22 against rotation. A knob 25 is provided on each pin 24. The latter functions not only as a set screw for clamping the movable coils in any horizontal position but as a convenient means for turning the coils.

In the alternative structure of Fig. 4 the

shaft 16' is coupled to the hollow shaft 26 through bevel gears 27. Shaft 16' and the coil carried thereby may be rotated by turning the knob 28. Pin 24' corresponds with pin 24 of Fig. 3 and is threaded into the hollow shaft 24. By holding knob 28 against rotation, the operator may turn knob 25' so as to move the end of pin 24' toward or away from spindle 23' thereby 10 clamping or unclamping the coils with respect to horizontal adjustments.

The two adjustments of the movable coils give a very much wider range of coupling than can be obtained with a single adjustment in a unit structure of moderate size 15 as will be quite obvious to those skilled in the radio art.

I claim:

1. An adjustable inductance coil mounting comprising a bearing member, a spindle about which said bearing member is rotatable, a pair of angularly disposed shafts journaled in said bearing, a pair of gears

inter-connecting said shafts, and means carried by one of said shafts for supporting 25 an inductance coil, said last-mentioned shaft having an axis of rotation disposed at an angle to the axis of rotation of said spindle.

2. An adjustable inductance coil mounting comprising a bearing member, a shaft 30 journaled in said bearing member, a coil supporting member carried by said shaft, a hollow shaft journaled in said bearing member and disposed at an angle to said first shaft, a pair of gears inter-connecting 35 said shafts, a spindle having an axis of rotation at an angle to both of said shafts, said bearing member being adapted to rotate about said spindle, and a set screw extending through said hollow shaft, the 40 end of said set screw being adapted to engage said spindle, said set screw being threaded into said hollow shaft.

In testimony whereof I affix my signature.

LOUIS G. PACENT.
